BOX CONNECTOR FOR FLEXIBLE
ELECTRICAL CONDUITS

William R. Woodring, Van Nuys, Calif.

Application May 10, 1946, Serial No. 668,748

2 Claims. (Cl. 285—6.5)

1

This invention relates to connectors for fastening flexible electrical conduits and the like to outlet boxes and terminal fixtures employed in electrical wiring installations.

An object of this invention is to provide a connector for use in the manner described which may be quickly and easily applied and installed without requiring the use of a nut or any screw threaded part or extraneous fastening elements.

Another object is to provide a connector such as described which is constructed and arranged so that the single operation of securing it around the conduit produces an automatic locking and securing of the connector to an outlet box or the like.

A further object is to provide a box connection of the character described which may be inexpensively stamped from sheet metal with integral fastening and locking elements which are subject to being manipulated by a special tool to tightly connect and lock a conduit to an outlet box or the like.

With the foregoing objects in view, together with such other objects and advantages as may subsequently appear, the invention resides in the parts and in the combination, construction and arrangement of parts hereinafter described and claimed, and illustrated by way of example in the accompanying drawings, in which:

Fig. 1 is a fragmentary side elevation of a box in which are installed a plurality of connections embodying the present invention.

Fig. 2 is a perspective view of a blank for forming one section of the connector.

Fig. 3 is a perspective view of a blank for forming the other section of the connector.

Fig. 4 is top plan view of the connector section formed from the blank shown in Fig. 3.

Fig. 5 is a top plan view of the other connector section which is formed from the blank shown in Fig. 2.

Fig. 6 is an end elevation of the connector as completed with the two sections loosely connected to one another.

Fig. 7 is an elevational view of the other end of the finished connector shown in Fig. 6.

Fig. 8 is a perspective view of the finished connector.

Fig. 9 is a fragmentary side elevation of a connector as when initially inserted into an opening in an outlet or like box, showing how the conduit may be inserted in the connector and the assembly is temporarily held in place preliminary to affixation of the connector to the box and conduit.

Fig. 9A is a fragmentary sectional view taken on the line 9—9 of Fig. 9.

2

Fig. 10 is a fragmentary part elevational part sectional view showing the connector and conduit as when the installation operation has been completed.

Fig. 11 is a side elevation of the special tool employed to fix the connector to the box and conduit showing in full lines the tool and connector as they would appear at the start of the operation of the tool, and illustrating in dotted lines how jaws of the tool are moved to fix the connector in place.

Fig. 12 is a view similar to Fig. 11 showing how the tool clamps the connector around the conduit by forcing the sections of the connector together and bending the locking tongues backward toward a section to which said tongues are connected.

Fig. 13 is a view similar to Fig. 12 showing the tool and connector as when the installation of the connector is completed, and

Fig. 14 is an end elevation of a modified form of connector embodying the present invention.

As shown in the accompanying drawings one form of connector embodying the present invention includes a tubular body formed of a pair of substantially semi-cylindrical sections A and B (see Figs. 4, 5, and 6) which may be stamped from sheet metal blanks C and D shown in Figs. 2 and 3 respectively. These sections are loosely connected to one another as shown in Figs. 6, 7 and 8 so that they may be adjusted while remaining connected, to bring corresponding ends thereof closely together for insertion through an opening E in a box F as illustrated in Figs. 9 and 9A. When thus applied to the box the outer ends of the sections A and B are widely spaced apart so that a flexible conduit G for electrical conductors (not shown) may be inserted into the connector as shown in Fig. 9.

Fig. 1 shows a box F with four of the connectors hereof connected thereto, the conduits being omitted from all but one of the connectors for the sake of clarity of illustration.

In accordance with this invention and as will be hereinafter more fully described, the sections A and B of the connector are constructed and arranged so that when the connector and the conduit therein are initially assembled as shown in Figs. 9 and 11, a special tool H as shown in Figs. 11, 12 and 13 may be applied and manipulated to clamp the sections tightly around the conduit and fix the connector tightly in the box opening E in one simple operation. Figs. 1, 10 and 13 show the finished installation.

The sections A and B of the connector are of similar formation and each is flared outwardly at one end to provide an arcuate lip or flange 1.

which is adapted to lie against the inner surface of the wall of the box F, thereby "hooking" the connector to the box. Each section is also provided at a point adjacent and spaced rearwardly or outwardly from the lip, with an outwardly struck knob or protuberance 2 which is adapted to abut the outer surface of the box and co-act with the lip for tightly fastening the connector to the box.

The section A is provided between its ends with outwardly flared side portions or flanges 3 and openings 4 through which latter are loosely extended bendable tongues 5 projecting from the side of the other section B. These tongues have outwardly bent hook-like terminals 5' which prevent withdrawal of the tongues from the openings 4 and maintain the sections loosely connected to one another. Due to flared sides or flanges 3, the section A is wider than section B which latter is subject to being partly telescoped by section A when the sections are brought together as shown in Figs. 11, 12 and 13. In this connection it should be noted that the section A has inwardly bent corner bearing portions 6 adapted to seat on corner bearing portions 7 on the section B as shown in Fig. 9A. These bearing portions serve as fulcrum points in adjusting the sections in initially applying the connector to the box and in the operation of clamping the sections around the conduit and fixing the connector in the opening E.

Each section is provided with a pair of inwardly projecting elongated ridges 8 on opposite sides of the knob 2 to act as stops for the end of the conduit G as shown in Figs. 9, 9A and 10. These ridges prevent the conduit from being extended through the connector into the box and as the ridges are arcuate and elongated they act as shields or guards covering the irregular and sharp end of the conduit and preventing damage to the insulation on electrical wires in the conduit as well as short-circuiting of such wires.

As a means for locking the conduit against withdrawal from the connector each of the sections A and B is provided interiorly with a pair of inwardly projecting spurs 9 and 10 which are spaced apart a greater distance than the threads on the conduit and bite into the conduit so as to prevent any turning, unscrewing or other movement of the conduit which would loosen it or the connector. The spur 9 is located so that the exterior depression 9' which is formed in punching the spur inwardly is disposed in predetermined relation to the flared sides 3 and tongues 5 and serves as a locator for the tool H as will be hereinafter more fully described.

The special tool H shown in Figs. 11, 12, and 13 includes a fixed jaw 12 formed at one end of a handle 13 and shaped to fit partly around the section B of the connector. Slidable on the handle 13 are jaw carrying members 14 and 15 which are movable responsive to actuation of a handle 16 pivoted at one end as at 17 to the member 15 and connected by means of pivoted links 18 to the handle 13. The member 14 carries a fixed jaw 19 having a spur 20 which is adapted to fit in the depression 9' in the section A of the connector. When the spur 20 is thus mounted in the depression 9' a pair of jaws 21 are disposed in position to contact the tongues 5 as shown in Figs. 11 and 12. The jaws 21 are in the nature of long arms pivoted at certain ends as at 22 to the member 15 and slidably guided in the member 14 with their outer ends 23 rounded and disposed for contact with the

tongues 5. A spring 24 is interposed between the slide members 14 and 15 and at one end bears on a keeper member 25 slidably supported in the member 15 and bearing against crank arms 26 or the pivoted ends 22 of the jaws 21. The other end of the spring abuts the member 15 being held in place by the inner end of the jaw 19.

It will now be seen that after the connector has been fitted in the opening in the box F as shown in Figs. 9, 9A and 11 and the conduit G has been inserted into the connector with its end abutting the ridges 8, the tool H is applied as shown in Fig. 11 with jaw 12 embracing the outer side of the section A and jaw spur 20 engaged in the depression 9' on the section B of the connector.

Upon now forcing the handles 13 and 16 together, the spring 24 is compressed allowing the member 15 to slide on the handle 13 toward the member 14, the movement of which latter is resisted by the connector then engaged by the jaw spur 20 on the member 14. As the member 15 moves outwardly relative to the member 14, the ends 23 of the jaws 21 are advanced against the outwardly flared ends of the tongues 5 as indicated by the dotted lines in Fig. 11 and as the pressure of the jaws of the tool against the connector is continued, the sections A and B fulcruming on the bearing portions 6 and 7 will be rocked into parallelism and clamped together as the tongues are bent back against the flared sides or flanges 3 on the section A. As the jaws 21 are further advanced, the sides or flanges 3 are bent inwardly against the sides of the section B. The conduit G being at this time inside the connector, acts as a mandrel and assures that the sections will be bent into tubular or cylindrical form in tight contact with one another and the conduit and at the same time wedged tightly in the opening E. Fig. 13 shows the tool as when the operation thereof has been completed and illustrates the connector as it would appear when the installation thereof has been completed. The tool may now be easily withdrawn by spreading the handles apart and removing the jaws from the connector.

It should be noted that when the sections A and B are forced together from position shown in Fig. 9 to the final position shown in Fig. 10, the lips 1 and knobs 2 and portions therebetween are forced into close and wedging engagement with said wall thereby permanently fixing the connector to the box in an electrically tight connection therewith. A similar electrically tight connection of the connector and conduit is assured by the tight clamping of the sections therearound and by reason of the spurs 9 and 10 biting into the conduit. These spurs also permanently lock the conduit in the connector and prevent any unscrewing or other movement which would tend to loosen the connector or the conduit therein.

It will now be apparent that the connector hereof may be inexpensively produced by simple die stamping operations and in having the particular integral fastening means and other provisions hereof may be quickly and reliably installed without the use of screw threaded parts or extraneous fastening elements and in such manner as to fully meet the requirements as to all building laws and codes.

As shown in Fig. 14 a modified form of this invention includes a tubular body member made of two semi-cylindrical sections A and B which

are identical with the sections A and B in the previously described connector except that the integral bendable tongues 5 and the particular openings 4 for said tongues are omitted. In place of these tongues I provide a U-shaped bendable wire fastening member 30, the legs 31 which are inserted through openings 32 in the section B, then through openings 33 in the section A and having their free ends 31' bent outwardly to prevent withdrawal of the member 30 and thereby loosely connect the sections together as a unit in substantially the same manner as effected with said tongues. This form of connector is applied to the outlet box in the same manner as the first described connector and is clamped around the conduit and fixed or locked to the outlet box in the same manner, the tool H operating through its jaws 23 to contact the ends 31' and bend them back so as to clamp the sections around the conduit and lock them to the box.

It is now apparent that connectors embodying the present invention are particularly advantageous in that the tubular body members thereof are so constructed and so equipped with fastening means at the ends thereof which are inserted into the outlet box, that said fastening means will automatically lock the connectors in tight engagement with the box incident to the single operation of clamping the body member around the conduit, whether this clamping operation is performed through the medium of the tongues or through the use of the bendable wire fastening shown in Fig. 14, or in face through use of any other clamping means.

While I have shown and described a specific embodiment of my invention, I do not limit myself to the exact details of construction set forth, and the invention embraces such changes, modifications and equivalents of the parts and their formation and arrangement as come within the purview of the appended claims.

I claim:

1. In a connector for fastening a terminal of a conduit to a fixture having an opening therein, a pair of substantially semi-cylindrical connector sections having certain corresponding ends outwardly flared to form retaining flanges adapted to project through said opening for contact with the inner surface of said fixture to prevent withdrawal of said sections from said opening, one of said sections having openings therein, bendable tongues carried by the other of said sections and loosely extended through said openings and bent outwardly at their free ends so as to prevent withdrawal of said tongues while loosely connecting said sections to one another subject to adjustment to bring the flared ends closely

together to permit of insertion thereof through said opening with the other ends spaced apart whereby a conduit may be inserted between and held by said sections, said tongues being bendable into position to hold the sections in conduit clamping position, and co-acting bearing portions on said sections arranged to contact one another when adjusting and moving said sections to fit in the opening and when applying to the sections a tool which is manipulated to force the section tightly together and bend the tongues into position for holding the sections clamped on the conduit and holding the flared ends in locked contact with said fixture.

- 15 2. A connector for the purpose described comprising a pair of sheet metal sections of arcuate cross section adapted to embrace and clamp therebetween an electrical conduit, one of said sections having openings therein, bendable tongues in integral formation with the other section and extended for free movement in said openings and having outwardly bent free end portions for retaining the tongues in said opening and said sections loosely connected with one another; and anchoring means formed integral with certain corresponding ends of said sections arranged to be disposed in position for anchoring of said sections within an opening in an outlet box or like fixture upon the clamping of said sections around the conduit following the insertion of said ends into said opening, said sections being constructed and arranged so that one will fit within and abut the other to form a substantially cylindrical body when the sections are forced together around the conduit, said tongues being bendable into position in which said sections will be drawn together and held in position for clamping the conduit and disposing said anchoring means in position for securely fixing the connector to said box or fixture, and locking spurs on said sections arranged to contact the conduit to prevent turning and withdrawal of the conduit.
